UNITED STATES PATENT OFFICE.

THOMAS DANQUARD, OF NEWARK, NEW JERSEY, ASSIGNOR TO AUTO PNEUMATIC ACTION COMPANY, OF NEW YORK, N. Y., A CORPORATION OF NEW YORK.

TRACKING MECHANISM FOR MUSIC SHEETS.

Original application filed November 4, 1921, Serial No. 512,886. Divided and this application filed July 25, 1923. Serial No. 653,686.

To all whom it may concern:

Be it known that I, THOMAS DANQUARD, a citizen of the United States, residing at Newark, in the county of Essex and State 5 of New Jersey, have invented a new and useful Tracking Mechanism for Music Sheets, of which the following is a specification.

This application is a division of the application for patent filed by me November 10, 1921, Serial No. 512,886 on a tracking mechanism for music sheets.

The object of this invention is to improve the operation of the automatic tracking mechanism employed in automatically operated musical instruments for keeping the perforated music sheet in proper lateral position on the apertured tracker bar, particularly when the music sheet is being rewound on the music spool. Automatic tracking mechanisms are now extensively employed but difficulty is encountered when using such devices in rewinding the music sheet on the music spool, because such rewinding usually takes place at such high speed that the automatic tracking mechanism does not have time to operate properly.

To overcome this difficulty, I have provided a locking mechanism which holds the 30 automatic tracking mechanism out of operation during rewinding which mechanism is also arranged so as to center the music spool or bring the same to an intermediate position and lock the same in such position 35 during rewinding.

The invention is illustrated in the accompanying two sheets of drawings, in which

Fig. 1 is a front elevation partly in diagram illustrating the application of my invention to a well known form of automatic tracking mechanism;

Fig. 2 is a plan of the pneumatics employed in such tracking mechanism;

Fig. 3 is a cross-sectional elevation on the line 3—3 of Fig. 2;

Fig. 4 is a cross-sectional elevation on the line 4—4 of Fig. 2;

Fig. 5 is a plan of the shut-off valve;

Fig. 6 is a plan of the shut-off valve seat; 50 and

Fig. 7 is a cross-sectional elevation on the line 7—7 of Fig. 5.

The invention will be best understood by a detailed description.

Referring to the drawings and in detail, 55 A designates the apertured tracker bar over which the perforated music sheet B is drawn from the music spool C by a take-up roll D, these parts being arranged in the usual spool box E. A gear 10 is mounted 60 on the take-up roll or the shaft thereof and is engaged by a driving pinion 11 secured on the end of a shaft 12 which can slide in its bearings in the spool box and in a framework 13 secured to the side of the spool 65 box. A pinion 14 is mounted on the end of this shaft and is driven by a chain 15 carried around the pinion 16 of the motor. A clutch 17 is mounted on the shaft 12. A gear 18 is loosely fitted on the shaft 12 and 70 journaled in the frame 13 and the same carries a clutch or pin 19 which the clutch 17 can engage. A chain 20 is carried around said gear 18 and a pinion 21 on the shaft 75 of the right hand music spool clutch or bearing. A shifter lever 22 is pivoted on the frame and engages the clutch 17. This shifter lever is connected by a link 23, armed shaft 24, link 25, pivoted lever 26, link 27 to the reroll lever 28 pivoted in the usual 80 manner, generally in the key bed of the instrument. This reroll lever connects by a link 29, lever 30 and link 31 to the motor governor and also by link 32 to a valve 33 arranged in a valve box 34 which valve is 85 used to connect the player action to the exhaust.

When the reroll lever is in the position shown in the drawings, the action will be connected to the suction or exhaust, and the 90 motor will be operated at a governed speed to rotate the take-up roll D to draw the music sheet forward over the tracker. When the reroll lever is shifted to the left the music spool will be rotated from the 95 motor at a high speed as the motor governor is cut out and direct connection is made thereto and at the same time the pneumatic action will be cut out of operation by the valve 33. This will cause the 100

music sheet to be rewound on the music spool at a high speed.

The parts as thus far described are of any conventional or approved form.

- 5 The automatic tracking mechanism shown as combined with the parts previously described consists of two operating pneumatics 35 and 36 which are connected to operate together by a bar 37, extending 10 from which is a link 38 which is attached to a pivoted bell crank lever 39, which is connected by a link 40 to a cam 41 mounted on a shaft 42. This cam 41 engages the end of the right hand music spool clutch 15 or bearing 43. The left hand music spool clutch or bearing 44 is engaged by a spring 45 which normally tends to force the music spool to the right. The tracker bar A is provided with two outer guide openings 20 46-46 and with two inner guide openings 47-47, the same being connected by pipes or tubes 460-460 and 470-470 to the valve box F of the tracking mechanism. There are two valve mechanisms arranged in said 25 box, one for each shifting pneumatic, the right hand one being illustrated in detail. The tube 460 for this valve mechanism is connected by passages under a diaphragm valve 48 and the tube 470 for this valve 30 mechanism is connected by passages to the top of a diaphragm 49 connected to operate the diaphragm valve 48. A passage with a bleed 50 extends from under the diaphragm valve 48 under a diaphragm 51 which controls a double valve 52. An exhaust or suction passage 53 is connected by a pipe 54 to the suction or exhaust. When all of the guide openings in the tracker bar are closed by the music sheet the diaphragm 35 valves 48-48 will remain down and the double valves 52 will also remain down and the suction or exhaust will be connected with both tracker pneumatics 35-36 and as they are opposed they will be locked in 40 central or intermediate position. When the music sheet wanders from one side far enough to uncover one of the guide openings 46, air will be admitted under the diaphragm valve 48 and then under the diaphragm 45 51 lifting a double valve 52 and connecting the shifter pneumatic controlled thereby to the atmosphere. This will allow the shifter pneumatics to operate just the right distance to shift the music sheet 50 automatically laterally on the tracker bar just the proper distance to insure correct registration during the forward travel. This operation will take place with an expanded or wide music sheet.

60 If a narrower music sheet is employed, when the same is in normal position the guide openings 46-46 will both be uncovered lifting both valves 52 and connecting both shifter pneumatics to the atmosphere. If such music sheet should wander laterally

one inner guide opening will be uncovered which will let air down on a diaphragm 49, will close the diaphragm valve 48 and will allow the double valve 52 controlled thereby to drop, thus connecting the proper shifter pneumatic to the suction so that the shifter pneumatics will operate to make just the right adjustment to keep the music sheet in proper registration.

This mechanism is of a well known type 75 and works substantially on the plan shown by the patent granted in my name No. 1,187,975, June 20, 1916. While this well known form of automatic tracking mechanism is illustrated, it is to be understood that my improvements hereinafter described can be applied to and used in combination with many other forms of automatic tracking mechanisms.

To provide for the centralizing and locking functions previously described for use in connection with any suitable automatic tracking mechanism the following devices are provided.

It will be seen that the pipes 460-460 and 470-470 are connected to a rotary valve 60 which is arranged on a seat 61 fastened on top of the valve box F. This valve seat 61 has holes extending down into the valve box so that when the valve is in the position shown in Fig. 7 the pipes 460-460 and 470-470 will be connected to the valve box F in the proper manner. The valve is held on said valve stem by a screw and a spring 63. The valve is provided with an arm 64 which is connected to some suitable point in the linkwork controlled by the reroll lever such as, for example links 640, lever 641, shaft 642, lever 643, link 644 as indicated in Fig. 1. Stops 65-65 105 may be arranged to be engaged by an arm 66 extending from the valve. These parts are arranged so that when the music sheet is being drawn forward for playing, the pipes 460-460 and 470-470 are properly 110 connected to the valve box F but so that when the reroll lever is shifted for rewinding all the connection between the pipes 460-460 and 470-470 is cut off. This is the same action as if all the guide openings in the 115 tracker bar were closed by the music sheet. The diaphragm valves 48-48 will remain down and the double valves 52-52 will also remain down and the suction or exhaust will be connected with both tracker pneumatics 35-36 as they are opposed. When the exhaust or suction is on both pneumatics as thus described, if one pneumatic is open more than the other the flexible leaf or fold at the bottom of such pneumatic will 120 have a larger area than the flexible leaf or fold in the other pneumatic. Hence the suction on the more extended fold or leaf will act on the pneumatics and will cause them to assume an intermediate or 125 130

practically central position and will lock them in such position. Thus, when the rewinding takes place the music sheet will be accurately drawn or 5 wound on the music spool.

The details and arrangements herein shown and described may be greatly varied by a skilled mechanic without departing from the scope of my invention as expressed 10 in the claims.

Having thus described my invention what I claim and desire to secure by Letters Patent is:—

1. The combination of an apertured 15 tracker bar, means for drawing a perforated music sheet from the music spool over the tracker bar for playing, means for rotating the music spool for rewinding, an automatic tracking mechanism for maintaining 20 the music sheet in proper lateral position on the tracker while tracking forward consisting of two opposed shifter pneumatics, valves for controlling the same, guide openings controlled by the music sheet, connections therefrom to said valves, and means for closing the communication 25 between the guide openings and the valves during the rewinding action.

2. The combination of an apertured 30 tracker bar, means for drawing a perforated music sheet from the music spool forward over the tracker bar for playing or for rotating the music spool for rewinding,

mechanism for causing this means to operate either way, an automatic tracker 35 mechanism for maintaining the music sheet in proper lateral position while traveling forward consisting of two opposed shifter pneumatics, the valves for controlling the same, guide openings controlled by the music sheet, connections therefrom to said valves, and valve mechanism for opening 40 and closing communication between said guide openings and valves operated by the mechanism which controls the action of the 45 music sheet forwarding or rewinding means.

3. The combination expressed in the above claim 2, the valve mechanism consisting of a rotary valve to which the connections from the guide openings are attached. 50

4. The combination expressed in the above claim 2, the valve mechanism consisting of a valve seat having openings to control said valves, and a rotary valve on said 55 valve seat having passage to which the connections from the guide openings are attached, said valve being movable to operative and inoperative positions and said passages being aligned with said seat openings 60 in the operative position of said valve and being closed by the valve seat in the inoperative position of said valve.

In testimony whereof I have hereunto affixed my signature.

THOMAS DANQUARD.
